UNITED STATES PATENT OFFICE.

CHRISTIAN A. CALLESON, OF NEW YORK, AND MARTIN CALLESON, OF BROOKLYN, NEW YORK.

DESIGN FOR A SUPPORTING-FRAME FOR ICE-CUTTERS AND ICE-CREAM FREEZERS.

SPECIFICATION forming part of Design No. 35,645, dated January 28, 1902.

Application filed December 11, 1901. Serial No. 85,530. Term of patent 14 years.

To all whom it may concern:

Be it known that we, CHRISTIAN A. CALLESON, a resident of the borough of Manhattan, and MARTIN CALLESON, a resident of the borough of Brooklyn, in the city and State of New York, citizens of the United States, have invented a new and original Design for a Supporting-Frame for an Ice-Cutter and Ice-Cream Freezer, of which the following is a specification, reference being had to the accompanying drawings, forming a part thereof.

Figure 1 is a view in front elevation of a supporting-frame for an ice-cutter and ice-cream freezer, and Fig. 2 is a side view of the same.

As shown in the drawings, the leading or material feature of our design consists in a body which presents a general rectangular form when viewed in front or rear elevation and an irregular outline when viewed in side elevation, the lower portion of the body being projected farther to the front and rear and the upper portion farther to the front than

the middle portion, a base for the body extended a distance beyond one side thereof, 25 and a gear-casing spaced from one side of the body by upper and lower brackets. The middle portion of the body is denoted by 1, the lower portion by 2, and the upper portion by 3. The base is denoted by 4, the gear-casing 30 by 5, and the upper and lower brackets by 6 and 7, respectively.

What we claim is—

The design for a supporting-frame for an ice-cutter and ice-cream freezer, substantially as herein shown and described. 35

In testimony that we claim the foregoing as our invention we have signed our names, in presence of two witnesses, this 6th day of December, 1901.

CHRISTIAN A. CALLESON.
MARTIN CALLESON.
